CLAIM

The ornamental design for a donut cooker, as shown and described.

DESCRIPTION

FIG. 1 is a perspective view of a donut cooker showing a first embodiment of my invention;
FIG. 2 is a top plan view thereof;
FIG. 3 is a side elevational view thereof;
FIG. 4 is an opposite side elevational view thereof;
FIG. 5 is a bottom plan view thereof;
FIG. 6 is a front elevational view thereof;
FIG. 7 is a rear elevational view thereof;
FIG. 8 is a perspective view similar to FIG. 1 illustrating a second embodiment of my invention;
FIG. 9 is a top plan view thereof;
FIG. 10 is a side elevational view thereof;
FIG. 11 is an opposite side elevational view thereof;
FIG. 12 is a bottom plan view thereof;
FIG. 13 is a front elevational view thereof; and,
FIG. 14 is a rear elevational view thereof.
